UNITED STATES PATENT OFFICE

140,446

DESIGN FOR A CURTAIN-DRAPERY BRACKET

Murl H. Pavese, Pacoima, Calif.

Application June 13, 1944, Serial No. 113,981

Term of patent 7 years

(Cl. D21—1)

To all whom it may concern:

Be it known that I, Murl H. Pavese, a citizen of the United States of America and a resident of Pacoima, in the county of Los Angeles, State of California, have invented a new, original, and ornamental Design for a Curtain - Drapery Bracket, of which the following is a specification, reference being had to the accompanying drawing forming a part thereof.

In the drawing, the figure is a perspective view of the curtain-drapery bracket, showing my new design.

I claim:

The ornamental design for a curtain-drapery bracket, as shown.

MURL H. PAVESE.
